UNITED STATES PATENT OFFICE

2,499,591

KEY RING

Charles H. Kraft, Kansas City, Mo.

Application September 9, 1946, Serial No. 695,729

3 Claims. (Cl. 70—459)

1

This invention relates to improvements in key rings and has particular reference to a two piece ring type.

The principal object of the present invention is the provision of a segmental, arcuate, tubular member having an arcuate slide rod mounted therein and adjustable to permit the removal of keys from the ring at either end of the tubular member.

Other objects are simplicity and economy of construction, ease and convenience of operation, and adaptability for use in carrying the various types and sizes of keys.

With these objects in view, as well as other objects which will appear during the course of the specification, reference will be had to the drawing wherein:

Figure 1 is a side elevation of a key ring embodying this invention.

Fig. 2 is an edge view of the ring.

Fig. 3 is a sectional view taken on the major plane of the ring with the ring opened at the right side.

Fig. 4 is a view similar to that shown in Figure 3 with the ring opened at the left side.

Fig. 5 is an enlarged sectional view taken on line V—V of Figure 1.

Fig. 6 is an enlarged sectional view taken on line VI—VI of Figure 1.

Fig. 7 is an enlarged sectional view taken on line VII—VII of Figure 1.

Throughout the several views like reference characters refer to similar parts and the numeral 10 designates a segmental, annular tube of substantially 300°, open at its opposite ends 12 and 14, and provided at its central portions with spaced apart indentures 16 forming stops 18 and 20 in the channel 22 of the tube 10. The indentures 16 are preferably made on the inside wall of tube 10, as shown, but will produce the desired stop regardless of their position about the periphery of the tube section.

The other member of the ring comprises a semi-circular rod 24 having its axial diameter substantially equal to the axial diameter of tube 10. Rod 24 is of a gauge suitable for a sliding fit in tube 10 and is substantially semicircular as shown, so that when it is in the position shown in Figure 1 it will overlap the end portions of tube 10, and will hug the walls of the tube sufficiently to prevent accidental movements of the parts. When the rod 24 is moved to the position shown in Figure 3, one end of 24 will contact the stop 18 to limit its inward movement when the slide and tube are opened at 26. By pushing the slide 24 in the reverse direction as shown in Figure 4 the opening will be at 28 and the other end of 24 will be against the stop 20. This double positioning of the slide rod 24 permits of better removal of the keys from the ring, due to the fact

that they may be removed from openings formed at either end of the ring tube.

In order to more accurately position slide rod 24 in the closed position, a notch 30 is formed 5 in the outer surface of rod 24 adjacent its central portion so that the operator may determine the degree of insertion of the rod in the opposite ends of the tube.

When the slide rod is positioned as shown in Figures 3 and 4, it may be forced sideways so as to be removed from the tube, furthermore, it may be assembled in similar manner, and will normally maintain its operative position.

What I claim as new and desire to protect by 15 Letters Patent is:

1. A key ring comprising a segmented annular tube member having open ends and provided adjacent its central portion with spaced apart internal stops, a single arcuate slide rod of shorter 20 length than and mounted for sliding adjustment in said tube, and adapted to contact one of said stops with its other end disposed in spaced apart relation outside said tube to form a gap therebetween and adapted to be moved to completely 25 close said segmented tube.

2. A key ring comprising an open arcuate tube member of substantially 300°, stops extending into the channel of said tube adjacent its central portion, and an arcuate slide rod fitted into said 30 tube to close said tube and to be moved so that its one end is positioned against one of the stops in said tube as its other end is positioned in spaced apart relation outside the other end of said tube to form a gap for the reception of keys.

3. A key ring comprising an open arcuate tube member of substantially 300°, spaced apart stops extending into the channel of said tube adjacent its central portion an arcuate slide rod of substantially 180° fitted into said tube with its one 40 end positioned against one of the stops in said tube as its other end is positioned in spaced apart relation outside the other end of said tube, and having a notch formed at its outer central portion.
